UNITED STATES PATENT OFFICE

158,104

COMBINED AUTOMOBILE FENDER AND
REAR QUARTER PANEL

Robert J. Lauer, Huntington Woods, Mich., assignor to General Motors Corporation, Detroit, Mich., a corporation of Delaware

Application March 24, 1948, Serial No. 145,308

Term of patent 7 years

(Cl. D14—6)

To all whom it may concern:

Be it known that I, Robert J. Lauer, a citizen of the United States, residing at 26090 York Road, Huntington Woods, in the county of Wayne and State of Michigan, have invented a new, original, and ornamental Design for a Combined Automobile Fender and Rear Quarter Panel, of which the following is a specification, reference being had to the accompanying drawings, forming part thereof.

Figure 1 is a perspective view of a combined automobile fender and rear quarter panel taken from the front and side.

Figure 2 is a rear perspective view thereof on a somewhat reduced scale.

The dotted line showing in the drawing figures is for illustrative purposes only.

What I claim is:

The ornamental design for a combined automobile fender and rear quarter panel, as shown and described.

ROBERT J. LAUER.
